UNITED STATES PATENT OFFICE.

JAMES I. FLANAGEN, OF PHILADELPHIA, PENNSYLVANIA.

DESIGN FOR A HANDLE-BRACKET.

SPECIFICATION forming part of Design No. 24,682, dated September 17, 1895.

Application filed August 13, 1895. Serial No. 559,190. Term of patent 7 years.

To all whom it may concern:

- Be it known that I, JAMES I. FLANAGEN, a citizen of the United States, residing in the city and county of Philadelphia, State of Pennsylvania, have invented and produced a new and original Design for a Handle-Bracket, of which the following is a specification, reference being had to the accompanying drawing, forming part thereof.
- 10 The leading feature of my design for a handle-bracket is, first, separated arms projecting from the attaching-ear, and, next, a segment of a ring on the outer end of the arm of the bracket.
- 15 In the drawing, which represents a perspective view of a handle-bracket embodying my

design, A designates attaching-ears of a handle-bracket, and B B designate converging arms, which are separated by the intervening space C. D designates a segmental ring on the outer ends of said arms B.

The upper and lower walls E E of the space C converge, the converging ends, which are in front, joining the arms B B, as at F.

What I claim is—

25 The design for a handle-bracket, substantially as described and shown.

JAMES I. FLANAGEN.
